Attorney

UNITED STATES PATENT OFFICE.

DANIEL W. HOUSE, OF MOBRIDGE, SOUTH DAKOTA.

LEGGING.

1,241,217.

Specification of Letters Patent. Patented Sept. 25, 1917.

Application filed March 10, 1917. Serial No. 153,942.

To all whom it may concern:

Be it known that I, DANIEL W. HOUSE, a citizen of the United States, residing at Mobridge, in the county of Walworth and 5 State of South Dakota, have invented certain new and useful Improvements in Leggings, of which the following is a specification, reference being had to the accompanying drawings.

10 This invention relates to certain improvements in leggings and it is an object of the invention to provide novel and improved means whereby the legging may be readily and effectively fastened in applied position.

15 The invention consists in the details of construction and in the combination and arrangement of the several parts of my improved legging whereby certain important advantages are attained and the device is 20 rendered simpler, less expensive and otherwise more convenient and advantageous for use, all as will be hereinafter more fully set forth.

The novel features of the invention will 25 hereinafter be definitely claimed.

In order that my invention may be the better understood, I will now proceed to describe the same with reference to the accompanying drawings, wherein—

30 Figure 1 is an elevational view illustrating a legging constructed in accordance with an embodiment of my invention;

Fig. 2 is a sectional view taken substantially on the line 2—2 of Fig. 1; and

35 Fig. 3 is a sectional view taken substantially on the line 3—3 of Fig. 1.

As disclosed in the accompanying drawings, L denotes a legging of conventional construction and wherein the longitudinal 40 marginal portions are adapted to overlie when the legging is in applied position.

The under marginal portion of the legging is continued, as indicated at 1, to afford a strap to underlie in a conventional manner 45 the arch portion of the foot. The upper end portion of the underlying marginal portion is extended, as indicated at 2, to afford a flap for a purpose to be hereinafter more particularly referred to.

50 Secured to the underlying marginal portion of the legging are a plurality of fastening members F adapted for swinging movement, and the lowermost of said fastening members is secured to the strap 1 at a point 55 below the body proper of the legging. As herein included, each of the fastening mem-

bers F constitutes an elongated loop adapted to be directed through an opening or button-hole 3 produced within the overlying marginal portion of the legging with the exception of the lowermost fastening member F and which lowermost member is intended to overlie the outer marginal portion of the legging when the same is in applied position.

50 In fastening my improved legging the loop ends of the fastening members are disposed through the loop of the fastening member immediately therebelow, while the loop of the uppermost fastening member F is adapted to engage or embrace the button 65 4 or the like secured to the outer face of the overlying marginal portion of the legging. The flap 2 is provided with the opening or button-hole 5, whereby the same may be engaged with the button 4 or the like after the 70 uppermost fastening member F has been operatively engaged with said button, whereby it will be at once self-evident that the fastening members F will be effectively maintained in locked relation.

80 From the foregoing description, it is thought to be obvious that a legging constructed in accordance with my invention is of an extremely simple and comparatively inexpensive nature and is particularly well 85 adapted for use by reason of the convenience and facility with which it may be assembled, and it will also be obvious that my invention is susceptible of some change and modification without material departure from the 90 principles and spirit thereof and for this reason I do not wish to be understood as limiting myself to the precise arrangement and formation of the several parts herein shown in carrying out my invention in practice, except as hereinafter claimed.

95 I claim:

1. In combination, a legging provided with longitudinal margins adapted to overlie, the under longitudinal marginal portion having its lower end extended to afford a strap to extend below the arch of the foot when the legging is in applied position, the upper end portion of said under longitudinal margin being extended to afford a flap, 100 the outer longitudinal marginal portion being provided with openings, a plurality of loop members secured to the under longitudinal marginal portion of the legging and to the strap, certain of said loop members 105 being adapted to be directed through the openings in the outer longitudinal margin 110

of the legging, each of said loop members being also adapted to be disposed through the loop immediately therebelow, and means carried by the outer marginal portion of the legging and coöperating with the flap and uppermost loop for holding the loops in assembled relation.

2. In combination, a legging provided with longitudinal margins adapted to overlie, the under longitudinal marginal portion having its lower end extended to afford a strap to extend below the arch of the foot when the legging is in applied position, the upper end portion of said under longitudinal margin being extended to afford a flap, the outer longitudinal marginal portion being provided with openings, and a plurality of loop members secured to the under longitudinal marginal portion of the legging

and to the strap, certain of said loop members being adapted to be directed through the openings in the outer longitudinal margin of the legging, each of said loop members being also adapted to be disposed through the loop immediately therebelow, the outer marginal portion of the legging adjacent the top thereof being provided with a button with which the uppermost loop is adapted to engage, said flap being provided with an opening whereby the same may also be engaged with the button.
